INVENTOR.

UNITED STATES PATENT OFFICE.

JOHN A. DOGENDORF, OF DETROIT, MICHIGAN.

FLASHING.

Application filed July 16, 1927. Serial No. 206,183.

This invention relates to flashing retainers, and the object is to provide a new and improved means for securing a flashing to a wall or chimney.

Heretofore, in this art, especially with metal roofing, it has been common practice where the roofing contacts the side face of a wall or a chimney to extend the metal a short distance and insert the edge in a groove commonly termed a raglin, provided between courses of bricks and secure the said edge therein by means of wedges. Such previous method is inadequate in that the wedge members become loosened after a period of use and the inserted edge of the roofing becomes displaced and it is also a rather expensive operation to secure the edge of the roofing in place in the manner stated.

My present invention seeks to obviate these various difficulties arising in the previous methods and to provide a separate channeled member which is laid in place between two courses of brick or stones at the time of erection of the wall providing a recess into which the edge of the roofing member may be readily inserted and avoiding the labor involved in removing a portion of the mortar, the member being flanged to engage over and securely fasten the flashing in place therein thus avoiding the use of wedges.

These objects and the various novel features of the invention are hereinafter more fully described and claimed, and the preferred form of construction of a flashing retainer embodying my invention is shown in the accompanying drawings in which—

Fig. 1 is a sectional view of a roof and a parapet showing the general arrangement of the flashing and flashing retainer.

Fig. 2 is an enlarged sectional view thereof at the time the edge of the flashing is introduced into the flashing retainer.

Fig. 3 is a similar section showing the completion of the securing of the flashing in place.

Fig. 4 is a perspective view of a strip of my improved flashing retainer.

Fig. 5 is a section longitudinally of two such strips which are inserted endwise one in the other laying a flashing of greater length than a single strip.

Fig. 6 is an alternative form of construction.

My improved flashing retainer consists of a member 1 which is preferably made of a copper sheet turned upon itself to provide a nar-

row channel indicated at 2 but slightly greater in width than the thickness of the metal sheet or flashing to be inserted therein. One of the edges 3 of this strip is bent approximately at a right angle outwardly as shown and the other edge 4 is also bent at a slight angle in the same direction as the member 3 providing a comparatively wide throat for the space 2. The sheet in its two opposite side walls is punched at regular intervals longitudinally of the strip as indicated in Fig. 4 to provide inwardly extending points 6 and 7 which are in registration when the sheet is folded and provide a means for holding the two side walls of the retainer in the desired spaced relation, the purpose being to prevent the walls of the flashing from being forced together when laid in the mortar and under pressure of the brick or stone thereabove. These retainer strips are preferably made of copper in order that they shall be rustproof and provide permanent installation so that, even though the flashing introduced therein may rust out, the retainer being a permanent installation is used when the roof is repaired and the edge of a new sheet introduced therein. Preferably the inner face of the strip forming the channel is turned or galvanized to prevent adherence of the flashing therein.

It will be readily understood from the drawing that in the laying of the wall or the chimney with which the flashing retainer is to be used, it is laid upon the brick or stone as the case may be at the desired height above the roof usually about six to eight inches and the wall is thereafter completed in the usual way. When laid in the wall the member is practically as shown in Fig. 2 with the edges 4 and 5 in the spaced relation as is shown in Fig. 4 which is the form at the time of installation providing a wide guide opening or throat for introduction of the edge 8 of the roofing sheet 9. Usually such metal roofing is laid over one or more layers of roofing paper indicated at 10 which extend across the roof surface and for a distance up the face of the wall as indicated at 11. The metal roofing plate 9 lays thereover and extends upward along the side wall or chimney or other structure as the case may be and the edge inserted in the retainer as previously stated. Subsequent to the insertion of the edge 8 of the sheet 9 as indicated in Fig. 2, the protruding edge 4 of the flashing retainer is hammered down to the position shown in Fig. 3.

Fig. 3 thus effectually securing the flashing in place and effectually preventing any accidental removal or leakage.

As previously stated, the flashing member 5 1 is made preferably in uniform lengths of from six to eight feet and, for use in walls of greater lengths than this, the flashing retainers are nested together at the end as indicated in Fig. 5 in longitudinal section—10 that is, the first member *a* receives the end of the member *b* in alignment therewith and the members need only be overlapped in this manner for a short distance the purpose being to prevent any break in the continuity 15 of the flashing retainer although it is to be understood that the invention is not confined to such use of the parts.

In Fig. 6 I have shown an alternative form 20 of construction of the retainer. With this form the upper wall of the strip is extended as at 10 beyond the lower wall which extends to approximately a point indicated at 11 and at the opposite end the lower wall is extended as at 12 beyond the end of the upper 25 wall at 13. The length of these extending portions may be as desired but preferably not more than two inches. In laying such strips in endwise relation the extending end portion 10 of the upper wall lays over the extending portion 12 of the lower wall of the adjacent strip and thus the joint which would then be formed between the end 10 of one strip and the end 13 of the adjacent strip does not align with the joint between the adjacent 35 ends of the lower walls 11 and 12 as will be readily understood. Also, in the laying of the metal roofing the joints between sheets thereof should break joints with the joints in the flashing retainer. This insures prevention of leakage.

In the construction of the retainer the depressions may be of much greater area than shown in Fig. 4 and of a form for instance as suggested in Fig. 6 at 14. These provide 45 pockets in the outer faces of the walls of the retainer in which the mortar engages and as these depressions are preferably formed in both walls, as in the form shown in Fig. 4, the projections thereof into the channel lie in 50 contact and prevent a collapse of the channel under pressure. Other means, however, may be provided to hold the channel walls in the spaced relation necessary for introduction of a flashing.

55 From the foregoing description it becomes evident that my improved flashing retainer is comparatively simple and inexpensive in construction; provides a means permanent in

character through which a metal or other character of sheet roofing may be readily 60 introduced and secured in place without liability of its later becoming loosened and permitting leakage. As to this point it is to be noted that the width of the member is such as to extend into the wall in which it is 65 supported to sufficient distance to insure its retention and, inasmuch as the member is laid in the mortar, the depressions forming the inwardly projecting points 6 and 7 become filled with the mortar thus insuring the 70 retention of the retainer in place.

I claim:

1. A flashing retainer consisting of a metal sheet bent upon itself providing a narrow longitudinal channel, an edge of one side wall 75 being outwardly bent providing a comparatively wide throat opening to the channel, means tending to prevent the side walls from collapsing under pressure, the retainer being formed in strips of the desired length with 80 the upper wall at one end extending beyond the lower wall and the lower wall at the opposite end extending beyond the upper wall whereby in laying the strips the projecting upper wall of one strip lies over the projecting lower wall of the other strip.

2. A flashing retainer adapted to receive the edge of a flashing, consisting of a sheet of non-corrosive metal bent upon itself to form a narrow longitudinal channel, the outer 90 edge of the walls defining the channel being so arranged as to provide a comparatively wide throat leading to the space between the said walls, the upper and lower walls defining the channel being approximately of the same 95 length and the upper wall extending at one end to beyond the end of the lower wall and the lower wall at the opposite end extending beyond the end of the upper wall, each of said 100 extensions having portions on the side of the bend extending inwardly from the plane of the respective wall whereby in laying the strips the projecting end of the upper wall of one strip lies over the projecting end of the lower wall of the adjacent strip with the 105 said inwardly extending portions practically in registration, at least one of said walls having depressions formed in its outer surface providing lugs for maintaining the walls in spaced relation, said lugs being at a distance 110 from the throat to permit insertion of the edge of a flashing.

In testimony whereof I sign this specification.

JOHN A. DOGENDORF.
